TIME STAMP RIBBON FEED MECHANISM

Joseph W. Faris, Cincinnati, Ohio, assignor to
The Cincinnati Time Recorder Company, Cincinnati, Ohio, a corporation of Ohio

Application November 18, 1935, Serial No. 50,271

7 Claims. (Cl. 101—336)

My invention relates to time stamps such as are used in mail receiving rooms, hotels, garages, and the like, to record the date and time of a transaction, and more particularly to ribbon feed mechanisms therefor. Such time stamps are usually clock actuated, and are provided with a series of printing wheels, adapted to print the year, month, day, hour (a. m. or p. m.) and minute of a recording. When a recording is made, these printing wheels are pressed against a type ribbon, which in turn makes an imprint upon a card or the like. In order that the imprints be clear and readily readable it is desirable that the type ribbon be periodically fed from one reel to the other, and back again. Many such devices are known and used in the typewriter and time recorder arts, but such mechanisms, on account of their bulk, are of little value in a time stamp, which is a small compact instrument.

It is an object of my invention, therefore, to provide a ribbon feed mechanism for a time stamp, which mechanism shall be very compact.

It is another object of my invention to provide a mechanism as above outlined, which will feed a type ribbon off one reel and onto another, and which will automatically reverse itself when the end of the ribbon is reached.

It is a further object of my invention to provide a mechanism of the type described, which will be actuated to slightly feed the ribbon at each operation of the time stamp.

These and other objects of my invention which will be set forth hereinafter or will be apparent to one skilled in the art upon reading these specifications, I accomplish by that certain construction and arrangement of parts of which I shall now describe a preferred embodiment. Reference is now made to the drawings which form a part hereof, and in which:—

Figure 1 is a side elevation of my device, with parts in section to show the construction.

Figure 2 is a detail view of one of the actuating ribbon guides.

Figure 3 is a cross sectional view taken on the line 3—3 of Figure 1.

Figure 4 is a cross sectional view taken on the line 4—4 of Figure 1.

Briefly in the practice of my invention I provide a casing 1, within which is mounted a clock motor which I have indicated generally at 2. The motor 2 is adapted to drive the printing wheels, which I have shown diagrammatically at 3, through appropriate gearing 4. The front of the casing is provided with a transparent opening 5 through which the clock face 6 may be

observed. The time wheels and ribbon reels and related mechanisms are all mounted upon an inner frame 7, 7a, and the type ribbon 8 passes from the reel 9 over the guides 10 to the reel 11.

The ribbon feeding mechanism comprises a plate 12, which is mounted for sliding movement on the frame 7 by means of the headed guide pins 13 which ride in the slots 14 in the plate 12. The plate 12 is urged to remain in the position shown in Figure 3 by the springs 15 which extend between the cross members 16b of the inner frame and ears 12a on the plate 12.

I have shown at 16 a steel ribbon, having drilled, reinforced end portions 16a and 16b. The end portion 16a is hooked over a headed pin 17 on the plate 12, and the ribbon passes downwardly under a guide member 18, and along the bottom of the casing toward the rear thereof.

At the rear of the casing the ribbon 16 passes around another guide member 18, and is connected by means of a spring 19 to one arm of a bell crank lever 20 which is pivotally mounted on a bracket 21 fastened to the base of the device. Thus, as the bell crank lever 20 is rocked in a counter-clockwise direction as seen in Figure 1, the ribbon 16 is pulled toward the right, and the plate 12 is pulled downwardly. The operating lever which carries the printing block 22 is shown at 23, and is journaled on the shaft 24 which is mounted in bosses 25 on the casing. An extension 23a of the lever 23, carrying a block 23b, is adapted to act as a stop to limit the backward movement of the lever 23 by coaction with the rear wall of the casing 1.

Also fixed upon the shaft 24 by means of a set screw 26a, is a lever 26, which carries a pin 27 at its lower end. The pin 27 is adapted to bear against an inclined plane 20a on the bell crank lever 20. It will be noted that the lever 26 is maintained in the position shown in Figure 1 by the compression spring 28 which bears against the rear wall of the casing 1 and against the inside of the lever 26, and is held in position by the bosses 28a and 28b. The lever 26 is actuated by the operating lever 23 upon contact of the portions 23c and 26b. It will be seen, therefore, that when the operating lever 23 is depressed, the portion 23c abuts against the portion 26b, rocking the lever 26 in a counter-clockwise direction against the compression of the spring 28.

The pin 27 rides up the plane 20a, rocking the bell crank lever 20 in a counter-clockwise direction, exerting a pull on the ribbon 16, and thus pulling the plate 12 downwardly. Upon release of the operating lever, the springs 15

and the spring 28 return the respective parts to their original position.

Referring now to Figure 3, at 29 and 29a on the plate 12, are mounted the links 30 and 31, the upper ends of which are connected by a cradle shaped link 32. The stop pins 33 and 34 on the plate 12 are adapted to be abutted by the ears 33a and 34a on the cradle shaped member 32 to limit the movement thereof to the right and left respectively. In order to resiliently maintain the assembly 30—31—32 in either the right or left hand position, I have provided a form of dead center mechanism. The links 35 and 36 are pivoted to the member 32 at 35a and 36a respectively, and are provided with slots 37 and 38 within which the headed pins 39 and 40, which are mounted on the plate 12, are adapted to ride. Springs 41 and 42 connect the upper ends of the links 35 and 36 with ears 41a and 42a on the plate 12. Thus the springs 41 and 42 tend to keep the assembly in the position shown in Figure 3, until by means which will be described hereinafter, the assembly is swung to the left, so that the pivot points 35a and 36a arrive on the other side of the center lines of the springs 41 and 42 respectively, when the same action as above described will again tend to maintain the status quo.

Also pivoted at the junctures of the links 30 and 31 with the member 32 are the pawls 43 and 44 which are provided with tail portions 43a and 44a respectively. Small springs 45 and 46 connect these tails with the member 32, and tend to keep the pawls in engagement with the ratchets 9a and 11a respectively, when the member 32 is in one or the other of its rest positions. As viewed in Figure 3, when the plate 12 is pulled downwardly as before described, the pawl 43 will ride over the teeth of the ratchet 11a, and on the return stroke of the plate 12, will dig in and rotate the ratchet 11a in a clockwise direction, thus feeding the type ribbon onto the reel 11. When the reel 11 is completely wound up and of course the reel 9 is completely unwound, the former and its ratchet 11a will resist further rotation. Assuming now that the plate 12 has been pulled downwardly, on its return stroke the movement of the pawl 43 will be resisted. The pawl 43 and the link 30 then act as a toggle and shift the assembly 30—31—32 to the left, to the other side of dead center, whereby the pawl 44 is brought into position to act upon the ratchet 9a in the same manner as was described in connection with the pawl 43 and the ratchet 11a.

It is to be understood that except insofar as made a part of the claims which follow, the type of machine to which my novel ribbon feeding mechanism is applied forms no limitation upon my invention, and that different forms of my preferred embodiment may be made without departing from the spirit of my invention.

Having now fully described my invention, what I claim as new and desire to secure by Letters Patent, is:—

1. In a time stamp having a type ribbon, a mechanism for feeding the same, and an operating handle, an operative connection between the said handle and the said mechanism comprising a steel ribbon. 5

2. In a time stamp having a type ribbon, a mechanism for feeding the same, and an operating handle, an operative connection between the said handle and the said mechanism comprising a thin flexible member having a relatively high tensile strength. 10

3. In a time stamp having a type ribbon, a mechanism for feeding the same, said mechanism comprising a slidably mounted plate adapted at each reciprocation to feed said type ribbon, and an operating handle for making an impression by cooperation with said ribbon, a connection comprising a thin flexible member having a relatively high tensile strength between said operating handle and said plate, whereby said plate is reciprocated at each actuation of said handle, for the purpose described. 15

4. In a time stamp having a type ribbon, a mechanism for feeding the same, said mechanism comprising a slidably mounted plate adapted at each reciprocation to feed said type ribbon, and an operating handle for making an impression by cooperation with said ribbon, a connection comprising a steel ribbon between said operating handle and said plate, whereby said plate is reciprocated at each actuation of said handle, for the purpose described. 20

5. In a time stamp having a type ribbon, a mechanism for feeding the same, and an operating handle, an operative connection between the said handle and the said mechanism comprising a thin flexible member having a relatively high tensile strength, and a spring. 25

6. In a time stamp comprising a casing, an operating handle, a type ribbon and means for feeding the same, an operative connection between the said handle and the said feeding means comprising a steel ribbon, and means to cause the said ribbon to conform its path substantially to the outline of the housing. 30

7. In a time stamp comprising a casing, an operating handle, a type ribbon and means for feeding the same, an operative connection between the said handle and the said feeding means comprising a steel ribbon, and means to cause the said ribbon to conform its path substantially to the outline of the housing, said last mentioned means comprising members fastened to the casing and bridging the ribbon, and having curved guide portions about which said ribbon is passed in changing direction thereof. 35

JOSEPH W. FARIS.
